BAYONET TYPE CAN CLOSURE

Augustine Davis, Jr., Cincinnati, Ohio

Application June 18, 1932, Serial No. 617,931

6 Claims. (Cl. 220—40)

This invention relates to can covers and retaining means of the bayonet type, more especially for bulk delivery cans suitable for long service and rough usage.

5 An object of this invention is to provide a can closure with a particularly simple and efficient bayonet type lock which is sturdy, durable, and can not be forced open by any pressures to which it may be subjected in service, and which will 10 remain reliably and tightly engaged in service. Another object of the invention is to provide a bayonet type can closure which has no obstructions on the outside of the can neck to interfere and become damaged in pouring or when the cap 15 is removed, and which offers a minimum of obstruction on the inside of the neck to pouring, handling, or cleaning the can. A further object is to provide such a closure having a minimum 20 number of parts. The preferred embodiment of 25 the invention requires only one part in addition to the can and cover.

In the accompanying drawing, forming a part 30 hereof:

Fig. 1 is a side elevation, partly in section, 35 showing the upper portion of a can with a cover and bayonet type lock embodying this invention;

Fig. 2 is an enlarged sectional view through the 40 cover and can neck shown in Fig. 1, this section being taken at right angles to the section in Fig. 30 1; and

Fig. 3 is an enlarged sectional view on the line 3—3 of Fig. 1.

The can 10 has a neck 12, which has a much 45 enlarged top 14, formed by rolling the metal outwardly over a wire, to provide a broad bearing area for contact with a gasket 16. The cover 18 is formed with a recessed annular elevation 20, and has a deep skirt 21 which extends downward 50 around the neck, this skirt being entirely free and separated from the neck.

Two reversely disposed internal tongues 22 are 55 secured to the under side of the depressed top 23 of the cover. These tongues extend downward from the top of the cover, and have short engaging tips 24 which terminate substantially at or adjacent the inner surface of the neck. These 60 tongues are formed on the ends of a single stamping 25, the transverse connecting portion of which is applied to the cover top, making an exceptionally strong combined construction of the cover and tongues and one that is very easy to manufacture. The stamping 25 is preferably welded 65 to the cover top. The tongue portions of this bar are hollowed downward and crosswise, as shown 70 at 26, by forcing the metal downward and in-

ward, thereby buttressing the tongues to the connecting portion. This hollow ribbing is carried outward into the lateral tips, at 27, with the result that the depending tongues are virtually unbendable both laterally and vertically.

5 Two grooves or inwardly extending corrugations 28 are formed in the can neck. These corrugations have a pitch and serve as threads under which the tongues 22 engage to lock the cover on the can after compressing the gasket sufficiently to produce a liquid-tight joint. Each of the grooves or corrugations 28 extends approximately 90° around the circumference of the can neck. The length of these grooves or corrugations may be made somewhat greater or less, but the 10 pitch of the corrugations is so related to their length that the tongues will not move as far as the ends of the corrugations, even after the gasket has become worn. I prefer to make the slope or 15 pitch of the corrugations 28 comparatively slight, 20 so that very considerable pressure can be exerted between the gasket and the bearing area on top of the neck with a comparatively small twisting pressure on the cover and the lock tends to remain 25 engaged without loosening due to jolting of the can.

The inwardly extending corrugations 28 have 30 flattened bottom faces 30 for engagement by the tongue tips 24. These flattened faces reduce the bending moment of the tongues and increase 35 the area of contact between the tongue tips and corrugations, thereby reducing the wear. The radial lines of the flattened faces 30 are substantially horizontal. When the tongues 22 exert a strong upward pressure against the flattened 40 faces 30, there is little or no resultant force tending to bend the tongues.

The extension of the skirt 21 of the cover 45 downward below the tongues protects the latter from serious injury when the cover is off.

Terms of orientation in the specification and 50 claims are relative since the position to the can opening and cover can be changed. Other changes and modifications may be made in the form of the embodiment illustrated without departing from the invention set forth in the appended claims.

I claim:

1. A sheet metal can and cover with bayonet 55 type locking means for holding the cover on the can, comprising two tongues connected to the under side of the cover and extending substantially vertically downward close to the inside wall of the can neck, radially extending tips at 60 the bottom ends of said tongues, and corruga- 65

tions in the can neck extending inwardly for a greater distance than the thickness of the can neck and formed with substantially horizontal flat faces on their lower sides for contact with the tips to hold the cover on the can by a substantially vertical pull so that the tongues do not bend inward and slip over the corrugations when the cover is clamped on the can with great force.

2. A sheet metal can and cover with bayonet type locking means for holding the cover on the can, including a one-piece metal stamping having a connecting portion extending substantially across the under side of the cover, and welded to said cover, and having substantially vertical tongue portions extending downward from the ends of the connecting portion and terminating at their lower ends in horizontal tips, inwardly extending corrugations in the can, each formed with a substantially horizontal flat face on its lower side, said corrugations being sloped to serve as screw threads and located in position so that said tips clamp against the flat faces to hold the cover firmly on the can.

3. An article of manufacture comprising a sheet metal can having a neck formed with diametrical-
ly opposed inwardly extending corrugations in the sheet metal and slightly inclined to serve as threads for radially extending tongues of a cover, said corrugations comprising bends in the sheet metal formed with a flattened face on the lower side of each corrugation in position to exert a substantially vertical thrust against the tongues when said tongues are clamped against the corrugations to hold the cover on the can.

4. An article of manufacture comprising a sheet metal can having a neck formed with diametrical-

ly opposed inwardly extending corrugations in the sheet metal and slightly inclined to serve as threads for radially extending tongues of a cover, said corrugations extending inwardly for a distance greater than the thickness of the sheet metal of the can and being formed with a flattened face on the lower side to increase the area of contact with the tongues of the cover and thereby reduce the wear caused by friction between said tongues and corrugations.

5. A sheet-metal can and cover with bayonet type locking means for holding the cover on the can, including a thread formed by corrugations in the sheet metal of the can, tongues connected to the cover and extending downward in the can substantially normal to the plane of contact of the cover on the can, and short tips at the lower end of each tongue extending under the thread in the can, said tips being of a length not substantially greater than the depth of the thread.

10. 6. A bayonet type can closure comprising a pressed metal cover shaped to fit over the top of a can, and a one-piece metal stamping having a connecting portion extending substantially across the under side of the cover and welded to said cover, substantially vertical tongues extending downward from the ends of the connecting portion and terminating at their lower ends in radial tips for clamping under projections on the inside of the can neck to hold the cover on the can, each of the tongues and the adjacent connecting portion being hollowed downward to form a ribbing which buttresses the tongues to the connecting portion, said ribbing extending outward into the tips to brace said tips against bending.

15. 20. 25. 30. 35. AUGUSTINE DAVIS, JR.
